US00D587100S

(12) **United States Design Patent**
Allsopp

(10) **Patent No.:** US D587,100 S
(45) **Date of Patent:** ** Feb. 24, 2009

(54) **WINDOW BLIND FRAME CLIP**

(75) Inventor: **Reginald Charles Allsopp**, Stockport (GB)

(73) Assignee: **Louver-Lite Limited**, Cheshire (GB)

(**) Term: **14 Years**

(21) Appl. No.: **29/248,161**

(22) Filed: **Jul. 31, 2006**

(30) **Foreign Application Priority Data**

Jan. 30, 2006 (EM) 473541-0003

(51) **LOC (9) Cl.** 08-05

(52) **U.S. Cl.** D8/356; D8/394

(58) **Field of Classification Search** ..... D8/105, D8/107, 333, 349, 354, 356, 358, 360, 360.1, D8/367, 373, 382, 383, 394-396, 400; D23/261; D26/38; 24/18, 197, 561; 174/153 G, 650, 174/656, 135; 242/400.1, 405.1, 405.2, 600, 242/603, 604, 604.1, 607, 608, 608.6, 608.7, 242/609, 916; 248/65, 74.1-74.4, 201, 214, 248/215, 229.26, 302, 304, 316.7, 316.8; 439/367, 369, 371, 472; 211/119; D13/153; 224/268, 269, 666; D6/580

See application file for complete search history.

(57) **CLAIM**

The ornamental design for a window blind frame clip, as shown and described.

DESCRIPTION

FIG. 1 is a lower front perspective view of the design;

FIG. 2 is a bottom view of the design;

FIG. 3 is a lower rear perspective view of the design;

FIG. 4 is a front view of the design;

FIG. 5 is a side view of the design;

FIG. 6 is a rear view of the design; and,

FIG. 7 is an upper front perspective view of the design.
